(57) **CLAIM**

The ornamental design for a toggle bolt, as shown and described.

DESCRIPTION

FIG. 1 is a perspective view of a first embodiment of the toggle bolt;

FIG. 2 is a front view of the toggle bolt of FIG. 1;

FIG. 3 is a side view of the toggle bolt of FIG. 1;

FIG. 4 is a plan view of the toggle bolt of FIG. 1;

FIG. 5 is a perspective view of a second embodiment of the toggle bolt, the only difference being in the addition of a third arrow shaped anchor means; and,

FIG. 6 is a perspective view of a third embodiment of the toggle bolt, the only difference being in the addition of a fourth arrow shaped anchor means.

The broken line showing of environmental structure is for illustrative purposes only and forms no part of the claimed design.
